FIREPLACE

Paul H. Lever, 2512 Carson, Redwood City, Calif.

Filed Oct. 21, 1963, Ser. No. 77,071

Term of patent 14 years

(Cl. D81—7)

FIG. 1

FIG. 2

FIG. 3

The dominant features of my design reside in the portions shown in full lines which portions are characterized by the specific configuration and appearance of the front panel member as shown.

I claim:

The ornamental design for a fireplace, as shown and described.
